UNITED STATES PATENT OFFICE.

HIRAM PLATT, OF COMO, MONTANA.

DESIGN FOR A MONUMENT.

61,144.

Specification for Design. Patented June 27, 1922.

Application filed June 7, 1920. Serial No. 387,516. Term of patent 14 years.

To all whom it may concern:

Be it known that I, HIRAM PLATT, a citizen of the United States, residing at Como, in the county of Ravalli and State of Montana, have invented a new, original, and ornamental Design for Monuments, of which the following is a specification, reference being had to the accompanying drawing, forming a part thereof.

I claim:

The ornamental design for a monument as shown.

HIRAM PLATT.
